UNITED STATES PATENT OFFICE.

THOMAS M. NICHOLS, OF ASHLAND, KENTUCKY.

HOISTING MEANS.

Original application filed November 22, 1919, Serial No. 339,828. Divided and this application filed January 3, 1921. Serial No. 434,656.

To all whom it may concern:

Be it known that I, THOMAS M. NICHOLS, a citizen of the United States, residing at Ashland, in the county of Boyd and State 5 of Kentucky, have invented a new and useful Hoisting Means, of which the following is a specification.

Attention is directed to my co-pending case No. 339,828, filed Nov. 22, 1919, and 10 setting forth sundry improvements in a crane. The device forming the subject matter of this present application, and the following description and claims, has been divided out of my co-pending application 15 above alluded to.

The present invention aims to provide a novel hoisting means, and mechanism for controlling the same.

It is within the province of the disclosure 20 to improve generally and to enhance the utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in 30 the precise embodiment of the invention shown can be made without departing from the spirit of the invention.

In the accompanying drawings:

Figure 1 shows in side elevation, a device 35 constructed in accordance with the invention; Figure 2 is a top plan; Figure 3 is a cross section on the line 3—3 of Figure 2; Figure 4 is a sectional detail disclosing the 40 brake; Figure 5 is a diagram showing the manifold and attendant parts.

The numeral 14 designates a support, which may be a turntable journaled for rotation on a truck 1 constituting a part of a crane. A shaft 38 is journaled in bearings 45 45 on the support 14 and carries a gear wheel 46 meshing with a pinion 46 on the shaft of an air compressor 47 mounted on the support 14. From the air compressor 47, a pipe 48 leads to an air tank 49 carried by the support 14. From the air tank 49, a pipe 111 50 leads to a manifold 110 on the support 14.

A gear wheel 50 is mounted on one end of the shaft 38 and meshes into a gear wheel 51 secured to one member 52 of a shaft, the said 55 member 52 being journaled in bearings 53

on the support 14. The gear wheel 51 meshes into a pinion 70 on the shaft 71 of an internal combustion engine or other motor, denoted by the numeral 72, the shaft 71 being journaled in a bearing 75 on the support 14. A clutch 75 is interposed in the engine shaft 71 and is operated by any suitable means, such as a lever 109. A reversing mechanism 107 of any desired sort is interposed in the engine shaft 71 and is operated 60 by any suitable means indicated at 108. A water tank 73 is carried by the support 14, a pipe 74 leading from the water tank to the jacket of the engine 72 for the purpose of cooling the engine.

A clutch member 54 is carried by the shaft part 52 and cooperates with a clutch member 55 splined at 56 to a shaft member 57 journaled in bearings 58 on the support 14. A drum 59 is secured to the shaft member 57, 70 a flexible element, or load-carrying line 104 being engaged around the drum. The drum 59 includes an end wall 60, grooved as shown at 61 to receive a brake strap 62, the ends of the brake strap being connected to the forks 75 63 of a lever 64 fulcrumed at 65 on a bracket 66 mounted on a cylinder 67 carried by the support 14. In the cylinder 67 a plunger 68 operates. A compression spring 69 surrounds the exposed portion of the plunger 68 80 and cooperates with the foot of the bracket 66, and with a washer 200 mounted on the plunger and held thereon by the lever 64. A spring 69 serves to maintain the brake strap 62 normally engaged with the end wall 60 85 of the drum 59, in braking or holding relation thereto.

A pipe 119 communicates with the manifold 110 and is controlled by a valve 120. The pipe 119 leads to the cylinder 67 which 90 controls the brake strap 62 of the load drum 59. Pipes 126 communicate with the manifold 110 and lead to a cylinder 127, the piston rod 128 of which is connected with one end of a lever 129 fulcrumed intermediate its 95 ends on the support 14, the other end of the lever being connected operatively with the part 55 of the clutch which connects the members 52 and 57 of the shaft shown in Figure 3. A pipe 131 leads from the manifold 110 to the cylinder 67 of the load brake mechanism. The pipes 126 and 131 are controlled by a valve 130.

The shaft 38 transmits motion by way of the gear wheels 45 and 46 to the air com- 100 105 110

pressor 47 pressure being transmitted from the compressor to the tank 49, by way of the pipe 48. The pressure in the tank 49 is carried to the manifold 110, through the 5 pipe 111.

The shaft member 52 is driven from the shaft 71 of the engine 72 by way of the pinion 70 and the gear wheel 51. The gear wheel 51 transmits motion to the shaft 38, 10 through the gear wheel 50.

Let it be supposed that it is desired to elevate the load which is carried by the line 104, and to reel the line 104 on the drum 59. Then, the valve 130 is operated to admit air into the appropriate one of the pipes 126, and into the cylinder 127, the rod 128 of the cylinder operating the lever 129, and the lever 129 shifting the clutch member 55 into engagement with the clutch member 54.

20 The aforesaid manipulation of the valve 130 admits air into the pipe 131, pressure being transmitted to the cylinder 67, and the lever 64 operating to release the hold of the brake strap 62 on the member 60 of the drum 59.

25 Thus, simultaneously with the starting of the rotation of the drum 59, the hold of the brake strap 62 thereon is released. A driving train now is established, comprising the internal combustion engine 72, its shaft 71, 30 the pinion 70, the gear wheel 51, the shaft member 52, the clutch element 54, the clutch element 55, the shaft 57 and the drum 59. The line 104 thus will be drawn in and reeled on the drum 59, an elevation of the load resulting.

As soon as the valve 130 is operated to disconnect the clutch elements 54 and 55, so that the load no longer is raised, the pressure delivered by the pipe 131 to the 40 brake cylinder 67 is released, the spring 69 reasserting itself to cause the brake strap 62 to cooperate with the end wall 60 of the drum 59. Thus, the load may be held at any position to which it may have been elevated.

Should it be desired to slack away the flexible element 104, and to lower the load, then, whilst the clutch members 54 and 55 are out of engagement, as aforesaid, the 50 valve 120 is manipulated, admitting air into the brake cylinder 67 by way of the pipe 119, the action of the spring 69 being overcome, and the hold of the strap 62 on the end wall 50 of the drum 59 being released. 55 The valve 130 couples up the drum 59 with the internal combustion engine 72, and releases the drum from operative connection

with the engine, the load holding means of Figure 4 being operated at the same time. The valve 120 is used only when it is desired to slack away the line 104, thereby to lower the load, as aforesaid, after the load has been lifted to the desired point. 60

Having thus described the invention, what is claimed is:

1. In a device of the class described, a winding mechanism including a shaft comprising driving and driven parts; a flexible element adapted to be wound on the driven part; a clutch forming a connection between said parts; a brake normally engaging the driven part; mechanism actuated by fluid pressure for operating the clutch to connect said parts; mechanism actuated by fluid pressure for releasing the brake when said parts are connected by the clutch; a motor operatively connected with the driving part of the shaft; a compressor; means for driving the compressor from the motor; means for conveying fluid pressure to both of said mechanisms, from the compressor; and a valve in the last specified means, operating to actuate both of said mechanisms simultaneously. 70

2. In a device of the class described, a winding mechanism including a shaft comprising driving and driven parts; a flexible element adapted to be wound on the driven part; a clutch forming a connection between said parts; a brake normally engaging the driven part; mechanism actuated by fluid pressure for operating the clutch to connect said parts; mechanism actuated by fluid pressure for releasing the brake when said parts are connected by the clutch; a motor operatively connected with the driving part of the shaft; a compressor; means for driving the compressor from the motor; means for conveying fluid under pressure from the compressor to both of said mechanisms; a valve in the last specified means and operating to actuate both of said mechanisms simultaneously; a second means for conveying fluid under pressure from the compressor to the mechanism for releasing the brake; 100 and a valve controlling said second means. 95

In testimony that I claim the foregoing as my own, I have hereto affixed my signature in the presence of two witnesses.

THOMAS M. NICHOLS.
